UNITED STATES PATENT OFFICE.

GEORGE W. PEASE, OF PITTSFIELD, MASSACHUSETTS.

UNION-GARMENT.

1,301,872.

Specification of Letters Patent. Patented Apr. 29, 1919.

Application filed September 10, 1918. Serial No. 253,381.

To all whom it may concern:

Be it known that I, GEORGE W. PEASE, a citizen of the United States, and a resident of Pittsfield, county of Berkshire, and State 5 of Massachusetts, have invented a certain new and useful Union-Garment, of which the following is a specification.

My invention relates to one piece or union garments and more particularly to work 10 suits or overalls, and has for its object to produce such an article of apparel as will yield or give in response to movements of the body of the wearer without placing undue strains on the material of the garment 15 or on the stitches.

A further object is to provide means for excluding dirt and dust from the inside of the garment when in use.

These and further objects will more fully 20 appear in the following specification and accompanying drawings considered together or separately.

I have illustrated one embodiment of my invention in the accompanying drawings in 25 which like parts are designated by similar reference characters, and in which—

Figure 1 is a rear view of a garment embodying my invention.

Fig. 2 is a horizontal section of the back 30 of the garment, the position of the section being indicated by the line 2—2 in Fig. 4.

Fig. 3 is a detail elevation of the rear of the garment as viewed from the outside.

Fig. 4 is a vertical section on the line 4—4 35 of Fig. 3, and

Fig. 5 is a detail elevation of the back of the garment as viewed from the inside.

This invention relates to garments of the same general type as that shown in my Patent 40 No. 1,272,706, issued July 16, 1918, which is provided with an opening in the front extending from the collar to the crotch to permit donning and removal of the garment and which may be closed by means of buttons 5 and buttonholes.

In carrying out the embodiment of the invention illustrated in this application I provide a garment having a body or upper portion 1 and a trousers or nether portion 2. 0 The upper and nether portions are attached together at the front and back, and a waistband 3 is permanently attached to the body portion from one side of the front opening entirely around the garment to the other 5 side of the said opening, and when the opening is closed the said waistband completely

encircles the body of the wearer. The waistband 3 is also permanently secured to the trousers portion from one side of the front opening to the other with the exception of a short distance at the back. The unattached portion of the waistband will produce a short slit 4 and the distance from one end of said slit to the other will constitute the only point in the girth of the garment where-in the upper and nether portions are not permanently secured together. It will be understood, however, that the waistband may be omitted and the garment formed of material of continuous length from the bottoms 60 of the legs to the collar, in which case the slit 4 may be cut through the material of which the garment is formed.

A member 5 forming a portion of the trousers and of a width at least equal to that 75 of the length of the slit 4 extends upward inside of the body portion 1 and is secured to the body portion at a distance above the slit and with its upper edge 6 preferably parallel thereto. The member 5 is preferably stitched to the back of the garment on parallel lines extended from the ends of the slit 4 upward to the upper edge 6 of the member. The member 5 therefore covers the slit on the inside of the garment and having a portion, the edge 6, unattached to the body will permit of relative movement of the body and trousers portions at that portion between the ends of the slit.

The slit 4 providing an opening from the 90 outside of the garment and the member 5 being unattached to the body at the upper edge of the member will provide a passage between the back of the garment and the member whereby dirt and dust from the outside 95 may find its way through the slit 4, and out over the edge 6 and soil the person of the wearer or such clothing as may be worn under the garment.

To provide against this contingency I employ a baffle element 7 which is stitched to the inside of the body portion 1 a short distance above the edge 6 and parallel thereto and to the slit 4. The lower edge 8 of the element extends to within a short distance of 105 the slit 4 and is parallel thereto and is not attached to the garment. The vertical edges of the element are stitched to the body portion preferably by the same stitches whereby the member 5 is secured in position.

The element will lie between the body of the wearer and the member 5 and will effec- 110

5
tually prevent the entrance of dirt and dust while at the same time it will not act to prevent relative movement of the body and trousers portions of the garment in response to bending and stooping movements of the wearer.

In practice I prefer to stitch the member 5 to the trousers portion in line with the stitching 9 in the upper edge of the waist-
10 band and to stitch the element 7 to the mem-
ber by means of parallel rows of stitches
10—10. When the element is in position on
the member the lower edge 8 of the element
15 will be approximately in line with the up-
per edge of the waistband 3 and its upper
edge will extend a short distance above the
edge 6 of the member.

When the garment is assembled a row of stitching 11 is run upward from one end of
20 the slit 4, through the vertical edges of the member 5 and element 7, across the top of the
member and element, and then downward securing
the opposite vertical edges of the member
25 and element to the back of the body portion
1, and then downward to the bottom line of
the waistband. The thread used in stitch-
ing the member and element to the body
portion 1 will be in such close proximity to
30 the thread by means of which the element is
preliminarily attached to the member 5 as
to appear as a single line of stitches.

It is obvious that the member 5 instead
of being stitched to the trousers portion may
be integral therewith and I have so illus-
35 trated the member in Fig. 4.

Instead of stitching the element to the
member and sewing both to the body of the
garment the stitching 10 may be omitted
40 and the member and element be attached to-
gether and to the body by means of the
stitches 11 or in any other approved manner.

In accordance with the provisions of the
patent statutes, I have described the prin-
ciple of my invention, together with the de-
45 vice which I now consider to represent the
best embodiment thereof; but I desire to
have it understood that the device shown is
merely illustrative and that the invention
may be carried out in other ways.

50 Having now described my invention what

I claim as new and desire to secure by Letters Patent is—

1. A garment comprising a body portion and a trousers portion permanently united at the back and front, there being a portion 55 of the garment at the back thereof at which the body portion is not secured to the trousers portion, a member attached to the trousers portion and extending upward inside of the body portion, means for securing said 60 member to the body portion at a point distant from that part of the body portion which is free of the trousers portion, an element stitched along its upper and side edges to the inside of the back of the body portion 65 to form a pocket open at its bottom only, the upper portion of the member being disposed within the pocket whereby the member may be moved relatively to the body portion and the element. 70

2. A garment comprising a body portion and a trousers portion permanently united at the back and front, there being a substantially horizontal slit at the back of the garment, the length of said slit being less than 75 the distance across the back of the garment, a member attached to the back of the trousers portion and extending upward inside of the body portion above the slit, means for securing the side edges of said member to 80 the body portion in lines substantially perpendicular to the slit, the upper edge of the member being unattached to the body portion, an element stitched to the body portion above the unattached edge of the member, 85 the sides of the element being stitched to the body portion and to the member, the upper edge of the member being disposed between the element and the back of the body portion of the garment and being unattached 90 to the element, the lower edge of the element being unattached to the member or to the body portion.

This specification signed and witnessed
this 9th day of September, 1918.

GEORGE W. PEASE.
